(57) **CLAIM**

The ornamental design for a transition for engine exhaust, as shown and described.

DESCRIPTION

FIG. 1 is a front-top-left perspective view of a transition for engine exhaust showing our new design.

FIG. 2 is a front view of the transition for engine exhaust.

FIG. 3 is a rear view of the transition for engine exhaust.

FIG. 4 is a left side view of the transition for engine exhaust.

FIG. 5 is a right side view of the transition for engine exhaust.

FIG. 6 is a top view of the transition for engine exhaust; and,

FIG. 7 is a bottom view of the transition for engine exhaust.
